BENJAMIN DENVER COPPAGE, OF WILMINGTON, DELAWARE.

DRUM WINDING-MACHINE.

1,342,532.

Specification of Letters Patent.

Patented June 8, 1920.

Application filed July 30, 1917. Serial No. 183,603.

To all whom it may concern:

Be it known that I, BENJAMIN DENVER COPPAGE, a citizen of the United States of America, and a resident of Wilmington, Delaware, have invented a new and useful Improvement in Drum Winding-Machines, which invention is fully set forth in the following specification.

This invention relates to improvements in winding webs of material, and more particularly to drum winders for paper-making machines.

In paper-making machines producing paper in web form, the finished paper is wound on a core to form a roll from which it may subsequently be unwound, trimmed, slit and again wound on separate cores. The second winding operation is usually performed by "drum-winders" which primarily include a laterally movable shaft on which are secured paper-receiving cores which are caused to rotate by power-driven drums frictionally contacting with the paper on the cores. As an example of a drum-winding machine of this type, reference is had to U. S. Patent No. 667,879 to Hazard, Feb. 12, 1901. In practice, it is found that winding paper in this manner presents serious objections, particularly when large winding machines are used. Seldom, the thickness of the paper is uniform. One edge may be thicker than the other. While, for example in newspaper, this difference may not amount to more than 1/10,000 inch, the cumulative difference in a full roll of newspaper becomes apparent in the production of imperfect rolls of paper. In winding machines which take the paper from slitters and wind the several webs on cores juxtaposed on a long shaft, adjacent rolls of paper if wound imperfectly sometimes have their ends telescoped, thereby ruining many hundreds of feet of paper. Again, in modern drum-winders, the paper-roll shaft which is several feet long and which is supported at its ends in bearings vertically movable, does not remain in alinement during its initial lateral displacement. The resultant of the forces acting on it causes it to bow upward until the paper roll reaches a diameter of about twelve inches. During the beginning of winding under such conditions, the pressure at the ends of the roll is very great as compared with that between the ends, resulting in increased winding

friction at the ends and causing the layers of paper extending back from the ends to take a spiral twist. This defect in the roll sometimes continues until a diameter of twelve inches is attained. The core of the roll twelve inches in diameter is thereby ruined. Further, the winding drums in large machines sag at their centers, thereby preventing uniform frictional contact along their lengths and further contributing to imperfect winding; and often, if not commonly, the long paper-roll shafts are more or less crooked and introduce winding troubles of their own.

My invention overcomes, in large part if not entirely, the above objections, and resides in applying to the ends of the laterally displaceable paper-roll shaft which receives the cores on which the paper is wound, a decreasing lifting force sufficient to relieve the upward bow in the shaft during the initial winding of the paper. While this may be accomplished by a variety of means, I prefer to use a weighted lever arm acting through a rock shaft having connections with the vertically movable bearings of the paper-roll shaft, the arm being so located on the rock shaft as to permit freedom of movement in its swings and so positioned in respect to the vertical as to decreasingly assist the upward lateral displacement of the paper roll during the initial winding of the paper, thereby overcoming the upward bow of the shaft.

My invention further resides in providing compensating means for overcoming the effects of unequal thickness of the selvages of the paper and for securing proper alinement of the winding drums and paper-roll-shaft. This means comprises adjusting devices adapted to angularly shift the axes of the paper-roll shaft and of the winding drums in respect to each other and to the paper-roll shaft. By properly adjusting the paper-roll shaft slightly out of horizontal, and adjusting the winding drums horizontally, frictional contact of the winding drums and paper-roll may be made to compensate for differences in thicknesses to produce a properly formed roll of paper.

Further, my invention resides in providing means for compensating for the sag of the winding drums while co-operating with the spreader whose function is to separate the slit webs as they pass to the winder. This

means consists in providing the winding-drums with a crown, or outwardly curved surface, which may follow, for example, the lines of the commonly employed spreader 5 exemplified in U. S. patent to Jefferies No. 674,919, May 28, 1901.

My invention also resides in providing means for compensating for the vibratory effects caused by crookedness in the paper-roll shaft. For such means I employ oppositely disposed springs which I place intermediate the bearings supporting the paper-roll shaft and the traveling support for the bearings, whereby both upward and downward thrusts of the ends of the shaft are cushioned by the springs.

In order that the invention may be more readily understood, reference is had to the accompanying drawings which illustrate, by way of example, my improvements applied to a drum-winding machine for winding paper. Such drawings, however, are intended to assist the description and not to define the limits of the invention.

25 In said drawings:—

Figure 1 is a side elevational view showing a two-drum winding machine provided with my improvements;

30 Fig. 2 is a front elevational view of the machine shown in Fig. 1;

Fig. 3 is a plan detail view, partly in section, showing the top of one of the paper-roll bearing supports with its stationary guide and the dial on one of the support 35 adjusting devices;

Fig. 4 is a detail view with parts broken away to show the manner of connecting one of the paper-roll bearings with its vertically movable sprocket chain;

40 Fig. 5 is a detail view in longitudinal section, showing a two-way ratchet device; and

Fig. 6 is a plan detail view showing adjusting means for the drum-winding bearings.

45 In the drawings, 1 is the base of the drum-winding machine, and 2, 2 are uprights. Drum-winding cylinders 3, 4, positively driven at the same or different speeds by any suitable means, have their hubs supported in bearing boxes 5, 6 which rest partly on a plate 7 supported on the frame of the machine and partly on sets of wedge-shaped adjusting blocks 8 held from side displacement by upturned edges of plate 7. These 50 wedges are clearly shown in Fig. 6 and each is provided with a slot for receiving a set-screw 9 which passes through a side extension 10 of the bearing and, by aid of a nut, clamps the bearing firmly to its seat. Loosening of the nuts on screws 9 permits the wedges to be moved endwise thereby laterally displacing, by their wedge faces, the bearing boxes and angularly adjusting the axes of the winding-drums in respect to each other. It is to be noted that means for ad-

justing the position of the bearings of the winding drums constitutes one feature of my invention. Uprights 2, 2 are each provided with a vertical guide 11 on which slides a member 12 provided at its lower end 70 with a bracket projection 13 constituting a bearing for the end of a removable paper-roll shaft 14 on which are secured the usual cores for receiving the paper web. Suitable means 15 for locking the shaft in its bearings are provided. At the upper ends of uprights 2, 2, held in suitable bearings, is a rock shaft 16 provided with weighted arms 17 located between the bearings and adapted to act through sprocket chains 18 and the 80 bracket bearing members 12 to relieve the accumulating weight of the paper as it is wound on the cores of the paper-roll shaft. This manner of assisting the lifting of the paper-roll is fully explained in U. S. Patent 85 No. 667,879 referred to above.

Means are also provided to prevent the sudden drop of the weighted arms 17 from their elevated position and, while any suitable means for the purpose may be used, I 90 prefer my improved means which consists of ratchet mechanism, Fig. 5, which may be connected to rock shaft 16 through gears 19, 20, 21, clutch 35, and gear 22. The detailed construction of this ratchet mechanism is 95 shown in Fig. 5 and comprises a shaft 23 keyed into a suitable recess in one of the uprights 2, and on this shaft is mounted a loose gear 19 one face of which is provided with ratchet teeth. The end of shaft 23 is provided with an interiorly threaded recess for receiving a threaded member 25 extending from a cap member 26 fitting over the end of shaft 23 and held against rotation by means of a key-pin 27 after the cap has been screwed down on a spring 28 retained in position by a barrel 29 the end face of which is provided with ratchet teeth designed to engage the companion teeth in the face of gear 19 under the action of spring 28. Barrel 29 is provided with an end closure 30 through which passes a rod 31 the outer end of which is provided with a hand wheel 32 fast thereto, the inner end having a cam member 33 integral therewith and adapted to be moved into and out of engagement with a reentering cam surface 34 formed on the end of the cap member 26. With the cam surfaces 33 and 34 out of engagement, as shown, the ratchet device is in idle position, but, if the cam surfaces are brought into engagement by turning the wheel 32 through a quarter turn, the companion ratchet members move into engagement. If the clutch 35 is thrown into engagement with pinion 21, the rotation of 100 rock shaft 16 is resisted by the ratchet means, since the power to turn pinion 19 through the gear train 22, 21, 20 is resisted by spring 28 until its tension is overcome, when it again offers its resistance thereby 105 110 115 120 125 130

effecting a step-down movement of the weighted arms. Suitable means are provided for hand rotation of rock shaft 16 to bring the weighted arms 17, and other parts connected therewith, into operative position. For this purpose, a hand-wheel 36 is loosely mounted on the end of the rock shaft, and to the wheel is made fast a pinion 37 also loose on the rock shaft. This pinion meshes with a large gear 20 which may be connected through clutch 35 with gear 22 fast to the rock shaft. By releasing the ratchet device in the manner above described, the hand-wheel 36 may be used to rotate the rock shaft into any desired position.

So much of the drum-winder as above described, except that portion relating to the adjustment of the drum-winding bearings and to the ratchet mechanism above described, is part of the old art and well understood, but a detailed description has been given of so much of the winder as to enable my improvements thereon to be more readily understood.

In order that the paper-roll shaft 14 may be prevented from bowing upward, I place on the end of rock shaft 16, outside of the standard 2 where freedom of movement may be secured, a weighted arm 38 and so position the arm on the rock shaft that it will exert a decreasing lifting power on the paper-roll shaft 14, when the latter is moving through its initial winding position, through the connecting medium of sprocket chain 18 and bracket bearing member 12. A suitable position for arm 38 to effect this result is where the arm is arranged horizontally or at an angle with and below the horizontal and on the side of the vertical permitting its lifting action on shaft 12. The proper position of lifting arms 17 in respect to weighted arm 38 is about 90° or more to the rear of the latter. These arms should be in their zenith position when weighted arm 38 is moving toward its nadir position.

To compensate for the unequal thicknesses of the selvage of the paper as it is wound on the paper-shaft 14, the bearings of the winding drums 3, 4 are provided with adjustments of the character above described, and adjusting means are also provided for raising and lowering either or both of the end bearing members 12 in respect to their supporting sprocket chains 18. In Fig. 4, I have shown the two ends of the sprocket chain 18 terminating in threaded link members 39, the threads on both links being either right-handed or left-handed. A sleeve 40 is inserted through an opening formed in a shoulder 41 of the member 12, and springs 42 are slipped over the ends of the sleeve, the lower spring being preferably stronger than its upper companion spring. Exterior threads are provided on the sleeve 40 to re-

ceive lock nuts 43 to hold the springs in place. An annular dial plate 44 is seated on the upper nut 43 and is secured thereto by a set-screw 45. The face of annular plate 44 is provided with graduations or other indicating means shown in plan view in Fig. 3. As a bench mark for these graduations, the corner of the guide 11 is peculiarly fitted for this purpose as it constitutes a fixed vertical line along which the dial moves. The interior of the sleeve is provided with threads to receive the threaded portions of the links 39 which are screwed into the sleeve and finally coupled with the end links of the sprocket chain. Owing to the fast connection of the sleeve 40 with the nut 43 and dial plate 44, any movement imparted to turn the latter causes the sleeve to turn up or down on threaded link members 39 and thereby raises or lowers the paper-shaft bearing member 12 on the sprocket chain 18. Any desired angular displacement of paper shaft 14 in a vertical plane can thus be made, thereby introducing an angular relation between the axis of the paper shaft and the horizontal plane in which the axes of the winding drums are made to angularly vary. By making proper adjustments of the paper shaft by aid of dial plate 44, and by adjusting the angular relation of the axes of the winding drums by aid of their adjusting wedges, compensation can be made for the objectionable effects in winding paper having different thicknesses at the edges. Should the paper shaft be crooked, as it usually is in the case of shafts used in large winding machines, the springs 42 cushion the irregularities of movement of the shaft and, in large measure, secure a resulting rotation that is smooth.

In order to overcome the sag in the winding drums and to facilitate spreading of the web, I have shown in exaggerated outline drum 4 provided with a crown 46 or convex surface tapering from the center toward both ends. One or both drums may be thus provided with crowns. I have shown only the front drum 4 as thus constructed, the rear drum being hidden from view.

The operation of the machine as thus far described will be readily understood from the foregoing description and, briefly stated, is as follows:—

It may be assumed that the web of paper is being taken from an unwinding stand and has passed the slitter-board and slitter, the trimming knives, and over the spreader bar, devices all well known in this art. The ends of the webs of paper are properly secured to cores which are mounted on and made fast to paper shaft 14 which has been lowered by manipulating hand-wheel 36 into position to contact with winding drums 3, 4. Paper shaft 14 is angularly adjusted in its vertical plane by manipulating dial 130

plate 44, the extent being determined by the inequality of thickness of paper to be compensated. The winding drums are also adjusted in their horizontal plane by aid of 5 the wedges 8 to properly position them in relation to the paper roll, the extent of the adjustments being dependent upon the irregularity of the paper and the direction of lead or run to the paper shaft, and sometimes 10 on the kind of paper. The weighted arm 38 will be in position to exert a decreasing lifting effect at the ends of the paper shaft through sprocket chain 18 and member 12, and arms 17 will exert, in their elevated 15 position, little lifting action on the paper shaft. The ratchet device is set in the manner described to permit a step-down movement of the rock shaft, and the clutch is thrown into engagement. Power is applied 20 in any suitable manner to drive the drums 3, 4 which, by reason of their frictional contact with the paper, force the paper shaft to revolve and begin winding. If the several adjustments have been properly 25 made, the paper shaft will revolve without bowing upward, even if the shaft is very long. The paper will be wound in separate rolls without telescoping of their ends, largely due to the use of crowned 30 drums, and the paper will be free from spiral creases, the center being wound as evenly as the outer layers.

While I have described the weighted arm 38 as positioned for lifting purposes, it may be used in other positions for effecting other results due to the fact of locating the arm outside the supporting frame, where it has freedom of movement. Further, while the compensating means have been described in connection with a paper-winding machine, they might be employed in machines winding other materials in endless form, and I therefore do not desire to be limited in their use to paper machines.

45 5. What is claimed is:—

1. In a winding machine of the character described, a laterally displaceable shaft on which material is to be wound, and a plurality of gravity actuated means for assisting the displacement of said shaft, one of said means being designed to move away from a neutral position and another of said means moving toward a neutral position as the shaft of material enlarges.
- 55 2. In a winding machine of the character described, a laterally movable shaft on which material is to be wound, traveling supports for the ends of said shaft, and weighted arms angularly displaced from each other having connections with said supports and designed to decreasingly assist the displacement of said shaft as the material on the shaft increases to a predetermined amount and afterward to increasingly assist said displacement.

3. In a winding machine of the character described, the combination of a laterally movable shaft on which material is to be wound, endless carriers provided with bearing brackets for said shaft, a rock shaft 70 having weighted arms angularly displaced thereon and operable by said endless carriers, said weighted arms when moving in one portion of their path having a resultant movement adapted to decreasingly assist 75 the displacement of said shaft as the material on the shaft increases to a predetermined amount.

4. In a machine of the character described, a laterally displaceable shaft on which material is to be wound, and a power-driven drum designed to rotate said shaft the surface of said drum being convex toward said shaft.

5. In a winding machine of the character 85 described, a laterally displaceable shaft on which material is to be wound, means for decreasingly assisting the displacement of the shaft as the material on the shaft increases to a predetermined amount, winding 90 drums for effecting rotation of said shaft, endless carriers each provided with means adjustable on said carriers, members engaging said means and having bearings for said shaft, and means for angularly adjusting the axes of said drums in relation to each other.

6. In a winding machine of the character described, a laterally displaceable shaft on which paper is to be wound, means for decreasingly assisting the displacement of the shaft as the material on the shaft increases to a predetermined amount, endless carriers 100 each provided with means adjustable on said carriers, and members engaging with 105 said means and provided with bearings for said shaft.

7. In a winding machine of the character described, a laterally movable shaft on which material is to be wound, means for decreasingly assisting the displacement of the shaft as the material on the shaft increases to a predetermined amount, winding 110 drums for effecting rotation of said shaft, endless carriers each provided with an adjustable sleeve having an indicating dial, a member engaging said sleeve and having yielding means opposing its movement in opposite directions on said sleeve, said member provided with bearings for said shaft, 115 and means for adjusting the axes of said drums in relation to each other.

8. In a winding machine of the character described, a rock shaft provided with a weighted arm, and ratchet mechanism comprising a driven member having connections with said shaft and a spring-pressed member provided with tension adjusting means, said second member being designed to yield under predetermined turning movement of 120 125 130

the rock shaft in one direction and to prevent movement when said rock shaft tends to move in the opposite direction.

9. Ratchet mechanism comprising a recessed stationary shaft interiorly threaded, a revoluble ratchet wheel on said shaft, a second non-revoluble ratchet member longitudinally movable on said shaft, a spring normally tending to move the second mem-

ber into engagement with said first member, and spring tensioning means comprising an abutment member for the spring having threaded engagement with said recess, and means for locking said member against rotation.

In testimony whereof I have signed this specification.

BENJAMIN DENVER COPPAGE.
